UNITED STATES PATENT OFFICE.

THOMAS ELLIOTT, OF BIRMINGHAM, ALABAMA, ASSIGNOR TO THE CINCINNATI CAR COMPANY, OF WINTON PLACE, OHIO, A CORPORATION OF OHIO.

RAILWAY-TRUCK-JOURNAL-BOX YOKE.

Application filed August 5, 1926. Serial No. 127,454.

This invention relates to improvements in railway truck journal-box yokes.

The general object of the invention is to produce a railway truck journal-box yoke which will form vertical guide ways for the journal-box combined with springs which will transmit the weight from the yoke to this box whereby the weight is rendered incumbent upon the axle journals so as to be carried by the wheels.

This general object is carried out by a structure, preferably of cast metal, in the nature of two upright members spaced apart to receive between them the journal box which it is to guide and themselves interconnected by cross members, between the upper of which cross-members and the upper face of the journal box coil springs are interposed in a manner to receive the weight from above and transmit it to the box.

Another feature of the yoke is that of making the upright portions hollow for the passage of the bolts by which the yoke is connected to the arch bars of the truck.

In the accompanying drawings,

Figure 1 is a side elevation of a railway car truck, otherwise conventional except for the incorporation therein of my improved yoke and box;

Figure 2 is an enlarged inverted plan view showing the lower face of the upper cross portion of the yoke with collars around which the springs are seated;

Figure 3 is a vertical sectional view of the yoke and journal box in elevation, this section being taken on the line 3-3 of Figure 4;

Figure 4 is a longitudinal sectional view taken through the yoke on the line 4-4 of Figure 2, showing connecting bolts in elevation;

Figure 5 is a horizontal sectional view taken on the line 5-5 of Figure 4;

Figure 6 is an enlarged side elevation of the yoke segregated from the other parts;

Figure 7 is a vertical transverse sectional view of the yoke taken on the line 7-7 of Figure 6.

In Figure 1 I have illustrated a type of railway truck manufactured by my assignee, The Cincinnati Car Company, but with my present invention incorporated therein. It will not be necessary to describe more of this truck than those features which enter into the use of the present invention.

Accordingly the numeral 1 indicates one of the top arch bars of a railway truck; the numeral 2 an intermediate arch bar and 3 a bottom arch bar. These bars are to be united or firmly secured to the yoke comprising a part of this invention. The yoke is in the nature of a frame composed of an upper member 4 with depending skirts 5 in the nature of flanges to make this structure more rigid, a lower member 6 also having flanges 7 to add to its strength, and of two uprights 8 each cast integral with the cross members and each hollow, as more particularly shown in Figures 4 and 5.

The upper cross member 4 is provided with tubular projections in the nature of collars 9 to form seats about which the upper ends of the coil springs 10 are fitted, the lower ends of these springs being fitted around like collars 11 formed on the upper member 12 of a journal box generally indicated by the numeral 13. This box is faced off on its vertical sides as shown at 14, and provided with a shoulder or flange 15 likewise faced off to form guides which fit and slide on the vertical members 8 of the yoke as clearly seen in Figures 4 and 5. This journal box is conventional in character except for the provision of these guides or ways.

It will now be seen that the yoke carries the journal box and that the yoke and journal box carry the coil springs 10, and that these springs so intervene between the two structures that the weight of the truck and its load is sustained by the journal box through the intermediary of these springs. The journal box and the vertical members of the yoke have relative movement, the former guided by the latter as the truck rolls over the rails and receives jars. So much for the vertical relative movements of the yoke and journal box. Then the journal box is guided laterally by the flanges 15 which work against the vertical members of the yoke and limit the outward thrusts of either journal box, and the journal boxes are carried forward by the yoke as the truck is advanced by the motive power.

Now with reference to the connection of the yoke to the truck frame, it will be observed, particularly in Figures 1 and 4, that the top arch bar 1 rests upon the yoke with the intermediate arch bar 2 intervening, while the lower arch bar 3 passes beneath

the yoke, and that through bolts 20 extend through the several arch bars and through the hollow vertical members 8 of the yoke as clearly seen in Figure 4.

Suitable nuts 21 are applied to the through bolts to draw the parts tightly together and make the structure rigid.

Thus it will be seen that the yoke so enters into the truck construction that it becomes a part thereof in order that it may carry the journal box 12 and, in effect, make a connection between the box and the frame generally. A very considerable number of the coil springs 10 may be interposed as seen in Figures 2 and 3, because of the facility of providing the necessary seats for them by reason of making the top member 4 of the yoke of sufficient area to provide such seats, while a like number of seats for the springs are formed around the projections 11 on the box itself.

This multiplicity of coil springs between the truck as a whole and the journal boxes affords an excellent spring equipment for the car. The natural law of these coil or helical springs is to vibrate rapidly and to yield to very minor as well as to major shocks. As I have positioned and situated this class of springs between my journal box and yoke, I produce a very desirable spring equipment and am enabled to use springs made of rods of comparatively small diameter without any risk of the springs tending to topple over by reason of the weight upon them. The vertical guidance of the journal box by the yoke and the secure seating of the springs to the box and yoke are factors which prevent the springs from toppling over sidewise but rather keep them in a vertical attitude so that they respond quickly to jars.

Any conventional journal plates or bushings 22 may be employed between the journal 23 and the journal box 12 as seen in Figure 3.

I prefer also to form the lower cross member 6 of the yoke in the manner shown in Figures 3 and 7 so as to constitute a seat 24 for the lower arch bar 3 to prevent any lateral shifting of the yoke at its lower end with respect to this arch bar.

Thus it will be observed that I have provided a combination of a yoke, journal box and springs, and a combination of yoke and arch bars of the truck which comprise a structure that is rigid and strong and yet in which the journal box has freedom of vertical movement while being amply secured and properly guided.

It will be understood that I desire to comprehend within my invention such modifications as may be necessary to adapt it to varying conditions and uses.

Having thus fully described my invention,

what I claim as new and desire to secure by Letters Patent, is:

1. In a railway car truck, the combination with a top arch bar, a lower arch bar and an intermediate arch bar, of a yoke secured to all of said bars and positioned between the top and intermediate bars and the lower bar and having vertical members forming guides, a journal box mounted in the yoke and guided vertically and laterally thereby, and springs interposed between the top of the yoke and the top of the journal box.

2. In a railway truck, the combination with the arch bars thereof, of a yoke comprising a casting forming upright hollow members constituting guides and transverse members, a journal box slidably mounted between said upright members and guided thereby, through bolts extending through the hollow members of the yoke and securing the bars to the yoke, and helical springs mounted between and attached to the upper part of the yoke and the top of the journal box.

3. In a railway truck, the combination with an upper and an intermediate arch bar, the one resting on the other, and a lower arch bar, of a yoke positioned between the lower bar and the intermediate bar and having hollow upright portions which form guides, through bolts passing through the several bars and said hollow members and having nuts to secure the parts together, a journal box having vertical surfaces fitting against two sides of either hollow member, the upper face of the box and the lower face of the upper member of the yoke having circular shoulders forming seats for springs, and coil springs fitted about said shoulders and locked between the box and that part of the yoke.

4. In a railway truck, the combination with a yoke comprising a casting having cross members and hollow vertical members, the latter forming guides, of a journal box having vertical faces which fit said guiding surfaces whereby the box is positioned and guided, and coil springs engaging at one end with the yoke and at the other end with the box and positioned between the yoke and box.

5. In a railway truck, the combination with a yoke consisting of a single casting having cross members and vertical hollow members, the latter forming vertical guides, of a journal box having right-angled vertical guiding surfaces embracing two sides of the vertical members, and coil springs positioned between the box and the upper part of the yoke and having a connection with each of them.

In testimony whereof, I affix my signature.

THOMAS ELLIOTT.
